(57) **CLAIM**

The ornamental design for a drill, as shown and described.

DESCRIPTION

FIG. 1 is a perspective view of an embodiment of a drill; FIG. 2 is a view of a first end of the drill of FIG. 1; FIG. 3 is a view of a second end of the drill of FIG. 1, the second end is at an opposite end of the drill from the first end;

FIG. 4 is a first side view of the drill of FIG. 1; FIG. 5 is a second side view of the drill of FIG. 1, the second side view is a view of the drill rotated ninety (90) degrees from the view depicted in FIG. 4;

FIG. 6 is a third side view of the drill of FIG. 1, the third side view is a view of the drill rotated one hundred eighty (180) degrees from the view depicted in FIG. 4 in a same direction of rotation as the view of the drill in FIG. 5; and,

FIG. 7 is a fourth side view of the drill of FIG. 1, the fourth side view is a view of the drill rotated two hundred seventy (270) degrees from the view depicted in FIG. 4 in a same direction of rotation as the view of the drill in FIG. 5.

The dashed lines in the drawings depict portions of the drill which form no part of the claimed design.

1 Claim, 7 Drawing Sheets
